MERCURY VAPOR TURBINE

Filed April 28, 1924

Lloyd T. Jones.
INVENTOR.

UNITED STATES PATENT OFFICE

LLOYD T. JONES, OF BERKELEY, CALIFORNIA

MERCURY VAPOR TURBINE

Application filed April 28, 1924. Serial No. 709,453.

The present invention relates to mercury-vapor turbines of a compact form suitable for driving airplanes, automobiles, etc.

The object of my invention is to provide a very compact form of mercury-vapor turbine that is readily transportable and which uses a minimum amount of propelling fluid.

For a very long time it has been recognized that in general it is desirable, wherever possible, to replace reciprocating by rotary engines. The comparative simplicity of the steam engine for automotive work is generally recognized, even though the steam engine be reciprocating, while the gas engine has been developed to such a remarkable degree that its performance is fairly satisfactory for automotive work yet it is with only the utmost care in construction and careful handling in its operation that it is sufficiently reliable to provide a means for the propulsion of airplanes. While the comparative reliability of airplane engines is granted it is also well known that the further development of aviation is awaiting the production of a lighter, more reliable and more economical engine.

The uses to which this turbine may be put are slightly different than the uses of the steam turbine. The chief advantage of the grouping here arranged is that it becomes possible to have a readily transportable unit embodying both lightness in weight and reliability in performance.

The blading system used is neither new nor unique since the type of blading used is dictated by the speed at which it is to be run, the vapor velocities, the power desired and other factors not all of which are under the control of the designer, as is well known in the art. Whether the turbine blading be such as to constitute an impulse, reaction or an impulse-reaction turbine is not considered a part of this invention since the type is dependent on the size of the turbine and the use to which it is put.

This turbine is designated as a mercury-vapor turbine though it is apparent that any other fluid possessing suitable physical properties might be used equally well.

This invention is not deemed to depend in

any way on the manner of supplying the heat necessary to vaporize the propelling fluid. The most satisfactory method, at present, consists of an oil vaporized by an air stream the air stream also supplying the oxygen for combustion.

The operation of this turbine and the manner in which it differs from others will be best understood by the following description taken in connection with the accompanying drawing.

The shaft, 1, which carries the stationary blade system, 2, is held in the clamp, 3, so that it may not rotate. The stationary blade system, 2, is held to the shaft, 1, by a collar, 19, and a nut, 20. The vaporization chamber, 4, and the condensation chamber, 5, together with the moving blade system, 6, constitute a rotor being provided at each end with shafts 22 and 23 from either of which power may be taken by the usual and well-known means in the art and as shown shaft 22 is provided with a propeller 24 for this purpose. The blade system, 6, is rigidly attached by welding to the waist of the housing formed by the vaporization and condensation chambers. The mercury, 7, which lies in the position indicated when the turbine is operating is vaporized by a flame passing in through an opening, 8, in the stationary part, 9, of the fire housing, a U bracket 25 being connected to part 9 and to a bearing member hereinafter referred to in order to maintain part 9 stationary. The portion, 10, of the fire housing is attached to the rotor. The fire housing is here arranged so that the waist of the rotor containing the blading system, 2 and 6, may be warmed. The vent, 11, allows the burned gases to escape.

The condensation chamber, 5, is provided with metallic flanges, 18, to aid in the cooling.

The rotor is supported in the bearings, 12 and 13, which also act as thrust bearings. Near the vaporization chamber the rotor is provided with a series of radiating flanges, 14, to aid in keeping the bearing, 12, sufficiently cool and to cooperate with bearing 12 to take the end thrust of said rotor. A packing ring, 15, keeps mercury from escaping between the rotor and the fixed shaft, 1. Two

channels, 16 and 17, communicate with the vaporization and condensation chambers respectively. By connecting these channels to vacuum pump and gauges the turbine may be evacuated and the pressures in the vaporization and condensation chambers may be read while the turbine is operating. Vacuum gauges 26 and 26' are provided as diagrammatically shown, in the drawings, for purposes of determining pressures in each of these chambers at their respective points of engagement with the passages 16, 17 and vacuum pumps are substituted for said gauges when it is desired to evacuate the chambers.

15 The mercury is vaporized in the chamber, 4; passes through the blading system, 2 and 6, into the chamber, 5, where it condenses and by centrifugal action is returned through the tubes, 21, to the vaporization chamber, 4. A difference in level of the liquid mercury just sufficient to balance the difference in pressure of the two chambers of the rotor is automatically maintained.

Let r be the radius of the rotor (containing the mercury) and W its angular velocity in radians per second. The mercury will be held against the periphery and uniformly distributed around the periphery by a speed such that

30 $W^2r = g$
where g is the gravitational acceleration. In the design contemplated $r = 1.25$ ft. Then $W = 5.07$ radians per second which is equivalent to 48.5 R. P. M.

35 After the turbine is started the centrifugal action on the liquid mercury in the return conduits will be sufficient to maintain a suitable difference in pressure between the boiler chamber and the condenser chamber as the following calculation indicates.

40 The turbine is designed to run at 1800 R. P. M. The working temperatures of the boiler and condenser, 800° F. and 400° F. respectively, are such that a vapor-pressure difference of 45 lbs./in.² will exist. The difference in level of the liquid mercury in the two chambers that is required to balance this pressure may now be calculated.

45 Let r be the radius of the rotating liquid mercury, ρ the density of mercury and a the area (projected) of the small conduit in which the liquid mercury stands. At the speed W the force due to a small length dr of the liquid in the tube will be:

$$50 dF = \rho a W^2 r dr$$

Integrating

$$F = \rho a W^2 \int_{R_1}^{R_2} r dr$$

55 Since this force is to balance the difference in pressure we may write

$$P_2 - P_1 = 1/2 \rho W^2 (R_2^2 - R_1^2)$$

60 65 As previously stated the probable value of R_2

is 1.25 ft. or 38 cm. Since the pressure difference will not exceed 45 lbs./in.² we have the following values:

$$W = 60\pi \text{ radians per second (1800 R. P. M.)} \quad 70$$

$$\rho = 13.6 \text{ gms/cc.}$$

$$P_2 - P_1 = 3 \text{ kg/cm}^2 (45 \text{ lbs./in}^2)$$

75 R_1 is then found to be 37.8 cm. It is thus seen that a head of less than 1 cm. of liquid mercury will balance the difference in pressure that will be experienced at the working temperatures.

80 It is on the basis of this calculation that centrifugal return of the condensed mercury is contemplated. This difference in level is dependent upon the speed of rotation and the radius of the rotor as well as upon the difference in pressure.

85 What I claim as new and desire to secure by Letters Patent of the United States is:—

86 1. A rotary engine, including a rotor having a condensation chamber, and a vaporization chamber, the latter of said chambers being of greater radius than the former, a turbine blade system in said rotor and means connecting said chambers so that condensed fluid in said condensation chamber is forced into said vaporization chamber by the centrifugal action of said rotor in any orientated position of said rotor. 90

95 2. In a rotary engine, a rotor having a condensation chamber and a vaporization chamber the latter of said chambers being of greater radius than the former, means for heating said vaporization chamber, a series of turbine blades in said rotor, a dividing partition between said chambers and a series of stator blades on said partition complementary to said first mentioned blades, and means connecting said chambers whereby the condensed fluid is returned by centrifugal force to said vaporization chamber in any orientated position of said rotor. 100

105 3. In a rotary engine, a rotor including a vaporization chamber and a condensation chamber, a turbine blade system in said rotor, said chambers being so arranged that both vaporization and condensation of a propelling fluid occur within said rotor, and means connecting said chambers and disposed longitudinally thereof whereby the propelling fluid is returned from the low pressure side of the system to the high pressure side by centrifugal force. 110

115 4. In combination with a vapor rotary engine having a turbine blade system, a vaporization chamber and a condensation chamber of means inter-connecting said chambers so that the propelling fluid is returned to said vaporization chamber by centrifugal force by the rotation of said rotor, means for heating said vaporization chamber, said means being adapted to heat vapor while passing through said blade system. 120

125 5. In a rotary engine, a rotor including a

vaporization chamber and a condensation chamber, a turbine blade system in said rotor, means for heating said vaporization chamber, said chambers being so arranged that 5 both vaporization and condensation of a propelling fluid occur within said rotor, and means connecting said chambers so that the propelling fluid is returned to said vaporization chamber in an uninterrupted flow by 10 centrifugal force due to the rotation of said rotor, said means comprising a conduit disposed longitudinally of said rotor and having one end in communication with said condensation chamber and its other end with 15 said vaporization chamber.

6. A rotary engine including a rotor having a vaporization chamber and a condensation chamber, the former of said chambers being of larger radius than the latter, a turbine 20 blade system in said rotor, means for increasing the pressure in one chamber and decreasing the pressure in the other, and longitudinally extending means connecting said chambers at substantially their radial extremities, 25 whereby upon rotation of said rotor, a difference in level of the propelling fluid proportional to the difference in pressures of the two chambers is automatically maintained irrespective of the position of orientation of 30 said rotor.

7. A rotor engine operated by mercury vapor, said engine comprising a condensation chamber and a vaporization chamber and impeller means interposed between and in longitudinal alignment with said condensation and vaporization chamber, said impeller means and vaporization and condensation chambers being rotatable as a unit, and one or more passageways extending from one chamber to the 40 other and in communication therewith whereby said mercury is returned by centrifugal force due to the rotation of said engine.

In witness whereof I have hereunto set my hand this 14th day of April, 1924.

45 LLOYD T. JONES.
